TO UNDERWOOD TYPEWRITER COMPANY, OF NEW YORK, N. Y., A CORPORATION
OF DELAWARE.

TYPE-WRITING MACHINE.

1,079,526.

Specification of Letters Patent.

Patented Nov. 25, 1913.

Application filed August 22, 1910. Serial No. 578,457.

To all whom it may concern:

Be it known that I, CHARLES HERMAN VOGEL, a British subject, residing at Vancouver, county of Vancouver, Province of 5 British Columbia, in the Dominion of Canada, have invented a new and useful Type-Writing Machine, of which the following is a specification.

The figure is a perspective view showing a 10 portion of the machine looking from the upper front right hand corner.

This invention relates to a new and improved typewriter, and especially to the 15 means for operating the type bars and connected mechanism.

An object of this invention is to afford in 20 a typewriting machine, a light touch by relieving the operator of a portion of the work necessary to actuate the type bars to their 25 fullest extent. This object may be attained by supplementing the action of the finger pressed keys by the action of power means for continuing the movement started by said keys. This power means may be of any 30 suitable character, and in this instance is shown in the form of electro-magnetic means adapted to actuate the type bars and connected mechanism directly and indirectly through the selective magnetic attraction of the electro-magnetic means.

A further object of this invention is to 35 provide positive means for holding all of the unactuated type bars in their normal position at rest, while the selected actuated 40 type bar is moving through its stroke. This object may be attained by providing electro-magnetic means for retaining by its attractive force, the unactuated type bars in their normal position at rest.

45 Other objects and advantages will herein-after appear.

Referring to the specific parts of this invention the member *a* constitutes the base of the machine to which the keyboard frame *b*, 45 and the main frame *c* and *d*, are substantially secured.

e represents one of the several keys for directing type to the platen, effected by pressing *e* downward, rotating the bar *g* through 50 the action of the crank *f*, thus drawing the link *i* downward through the action of the crank *h*, and rotating the journal *k* through the action of crank *j*, turning the type-lever *l* through a space by which the type *m* will 55 be brought to the point *n*, which is at the

center of the circular plate on which the several rotating rods, as *k*, are mounted, and at which center *n* all of the various type will strike. The rotating action of *g* toward the right will force the plate *A* to the right by 60 means of the crank *p* pressing against the pin *o* secured in the plate *A*, thus bringing into contact the electric wires *z*, and the extension of the electric conductor *D* from the battery *E*, closing an electric circuit through 65 the battery, which energizes the electro-magnet *F* and tends to hold all the type at the position of rest adjacent to it. The plate *A* moving to the right through the action before described also forces the spring *r* to the 70 right, thus rotating the ratchet wheel *s* (having teeth around its periphery) to the extent of one tooth, bringing the point of the tooth in contact with the shoe *v*, forming an extension of the electric wire *v*, which completes an electric circuit through the ratchet wheel *s* the wire *u* and battery *x* and wire *v*, 75 thus energizing the circular electro-magnet *y*, ending to draw the type to the point *n*, it being understood that there would be soft 80 iron connected with each of the type, which will be attracted by the magnets. This in the accompanying drawing may be the bar *l'* holding the type in on the type bar *l*.

t is a spring to prevent the return motion 85 of *s* after *r* has turned it to the extent of one tooth.

It will also be understood that in rotating the rod *g* to the right the type *m*, joined to *e* by the mechanical parts before mentioned, 90 would be partly raised toward *n* before the contact between *z* and *D* would take place. Consequently the magnetic influence from *F* on *m* would be very slight compared with the same influence on the adjacent type; 95 about at the same instant the contact between *v* and *u* would be completed through *s* and the magnet *y* would draw the type *m* very rapidly to its point *n* on the platen.

It will be seen that the contact between *v* 100 and *u* would be immediately broken as the point of the tooth passes the extension from *v*, thus allowing the type, through the force of gravity and such springs as may be later mentioned or engaged, and through magnetic influence of *F*, to return to its position 105 of rest.

While the magnet *y* may be depended upon to draw the selected type bar which has been moved away from its fellows a suffi- 110

cient distance by the depression of one of the keys *e*, a more positive means may be depended upon to bring it up to close juxtaposition to the platen and under the sphere of attraction of the magnet *y*, where the last imprinting impulse to the type bar may be given by the attraction of the magnet *y* to the metallic portion of the type bar, or to the supplementary soft iron armature placed on the type bar.

10. By a proper adjustment, it will be seen that the type bars can be brought up to striking position, and attracted at the last portion of the stroke, to give the desired impression which will be in the character of a pressure stroke rather than an impact stroke, thus eliminating considerable noise incident to the operation of the typewriter. The positive means for raising the type bars beyond the point reached through the actuation of the keys *e*, will now be described. The cylinder *C*, secured to the frame *d*, represents an electro-magnet which may be operated from battery *x*, through the action of *v*, *s* and *u*, and to be energized soon after the plate *A* has started its movement toward the right, thus attracting the bar attached to *B*, which will engage with the plate *A* and draw the same rapidly toward the right, facilitating its rapid movement and relieving the operator from the exertion of such power from the pressure of the key *e*. The pin *q* would also engage on the left side of the crank *p*, which previous to the electric circuit energizing *C* would be raised sufficiently for such an engagement. While similar pins in the plate *A*, in connection with similar members connected with other keys and type would pass over the tops of said cranks and not affect them. The action of pin *q* would, through a mechanical process tend to raise the type *m* rapidly to the center *n*, causing a similar result to that effected by the magnet *y* before described.

15. As has been stated above, each key in the set or bank of the typewriter, is operatively connected in the manner described, to the plate *A*, which is therefore in the nature of a universal bar, and can be used to control the escapement of the carriage, (not shown), to feed the same properly, in order to allow for the proper spacing of the successive letters. In order to indicate such an arrangement, the plate *A* is shown as provided with a pin 37 which engages in a slot in a rocker 38, pivoted at 39, and having connected thereto a link 40, which communicates with any suitable type of escapement mechanism provided for the carriage.

20. Variations may be resorted to within the scope of the invention, and portions of the improvements may be used without others.

I claim:

1. The combination with a plurality of typewriting elements, of means for operat-

ing one of said elements individually, and electrically operated means for holding any other similar element inactive whenever one of said elements has been actuated.

2. The combination with a plurality of typewriting elements each adapted to be individually operated, of electro-magnetic means for holding any other similar element at rest after one of said elements has been actuated.

75 3. The combination with a typewriting element, of electro-magnetic means for operating said element by direct attraction thereof, and separate power-driven means for supplementing the action of said electro-magnetic means.

4. The combination with a typewriting element, of electro-magnetic means for operating said element by direct attraction thereof, and electro-magnetic means for supplementing the action of said first-mentioned electro-magnetic means.

80 5. The combination with a typewriting element, of means for pulling said element in one direction, means for pulling said element in another direction, and selecting devices for controlling the actuation of said element by either of said means, by initially moving said element to bring it under the influence of either of said means.

95 6. The combination with a typewriting element, of a pair of electro-magnets adapted to pull said element in opposite directions, selective means for determining which of said magnets shall pull said element, and a mechanism controlled by said selective means for exciting both of said magnets concomitantly.

7. The combination with a type bar, of a key for starting the movement of said bar, additional means for continuing the movement of said bar, and electro-magnetic means for effecting the final portion of the stroke of said bar.

105 8. The combination with a type bar, of a key for effecting the initial movement of said type bar, electro-magnetic means brought in play by the movement of said key for continuing the motion of said bar, and additional electro-magnetic means for effecting the final movement in the striking stroke of said type bar.

110 9. The combination with a type bar, of an electro-magnet for positively holding it inactive unless first set in motion, means for positively continuing its motion when once moved, and additional electro-magnetic means for causing it to be accelerated just before the type strikes the sheet.

115 10. The combination with a type bar, of means for positively holding it, power means for positively continuing its motion when once moved, and additional power means for positively accelerating the end of its stroke.

120 11. In a typewriting machine, in combina-

130 65

tion, a universal bar, a key, a rock shaft actuated thereby, a cam plate carried by said rock shaft adjacent to said universal bar, a pin carried by said universal bar normally 5 engaging the edge of said cam, and adapted to give said universal bar an initial movement when said cam is actuated by said key, a second pin carried by said universal bar adapted to actuate said cam, electrical means 10 for completing the movement of said universal bar after said initial movement, a type bar, and means actuated by said rock shaft to drive said type bar.

12. A typewriting machine having means 15 for imparting motion to the type members electrically, and comprising a type-bar, an electro-magnet for moving said type-bar, an electro-magnet for holding said type-bar, a soft iron member fast to the type-bar acted 20 on by said magnets, and a universal bar for opening and closing the circuits of said magnets.

13. A typewriting machine having type members, means for imparting motion to the 25 type members electrically, comprising two electro-magnets, a soft iron member on the type member, a universal bar, means operated through said universal bar for opening and closing the circuits, and other means operated through said universal bar for imparting motion to the type.

14. A typewriting machine having means for imparting motion to the type members electrically, and having a holding electro-magnet and a driving electro-magnet, a soft iron member on each type member, and a universal bar for opening and closing the circuits.

15. The combination with a type-bar and 40 a universal member, of an electro-magnet for starting said type-bar through said universal member, and moving it into the field of another magnet which accelerates the end of the stroke.

45 16. In a typewriting machine, the combination with a key and a universal bar initially moved thereby, of a type connected to said key, an electro-magnet energized by said initial movement, and a lost motion connection between said electro-magnet and said universal bar for completing the action of said type.

17. In a typewriting machine, the combination with a key and a universal bar initially moved thereby, of a member connected to said key adapted to be caught by said universal bar, an electro-magnet energized by said initial movement so that it completes the motion of said universal bar, and a type 60 connected to said key so that said electro-magnet completes the action of said type.

18. In a typewriting machine, the combination with a key and a type connected to said key, of a universal bar moved by the 65 initial operation of said key, a magnet ener-

gized by said initial movement for holding said type against movement unless moved by said initial operation of said key, an electro-magnet energized by said initial movement for completing the motion of said universal bar, and an electro-magnet energized by the operation of said key for completing the type stroke. 70

19. In a typewriting machine, the combination with a key and a type connected thereto, of a universal bar moved by the initial operation of said key, an electro-magnet energized by said initial key movement to complete the movement of said key and type, a lost motion connection between 80 said magnet and said universal bar, and a magnet energized by the operation of said key for accelerating the type-stroke at its end.

20. In a typewriting machine, the combination with a key and a type initially moved thereby, of an electro-magnet for holding said type if not so initially moved, an electro-magnet for completing the movement of said type, an electro-magnet for accelerating said completion of movement, 90 a contact for determining when said holding magnet shall become effective, and a separate contact for determining when said moving magnets shall become effective. 95

21. In a typewriting machine, the combination of a key and a type connected thereto, of a universal bar initially moved by said key, an electro-magnet for completing the movement of said universal bar and thereby moving said type, an electro-magnet for accelerating the type stroke near the completion thereof, a single contact for making said magnets effective, a separate magnet for holding the type if not so initially moved, and a separate contact for said holding magnet. 100

22. In a typewriting machine, the combination with a type bar and a key, of a universal bar for receiving a partial stroke 110 from the key, an electric circuit, a toothed member in said circuit moved by said partial stroke to the extent of one tooth, a shoe in said circuit for striking a tooth on said toothed member when turned to make and break the circuit, and a magnet in said circuit for drawing said universal bar to complete its stroke to operate the type bar. 115

23. In a typewriting machine, the combination with a type bar and a key, of a 120 universal bar, connection between the key and said bar to impart thereto a partial stroke, an electric circuit, a toothed member in said circuit moved by said partial stroke to the extent of one tooth, a shoe in said circuit for striking a tooth on said toothed member when turned to make and break the circuit, and a magnet in said circuit for drawing said universal bar to complete its stroke, to operate the type bar. 125

- 4
24. In a typewriting machine, the combination with a type bar and a key, of a rock shaft, a stem and crank from the key to rock said shaft, a universal bar for receiving a partial stroke from said shaft, an electric circuit closed and opened by said partial stroke, and a magnet in said circuit for drawing said universal bar to complete its stroke, to rock said shaft and operate the type bar.
25. In a typewriting machine, the combination with a type bar and a key, of a rock shaft rocked by the key, a universal bar, a dog on said shaft, a pin on said bar struck by said dog to impart a partial stroke to the bar, an electric circuit closed and opened by said partial stroke, a magnet in said circuit for drawing said universal bar to complete its stroke, and a pin on said bar striking said dog during said completed stroke to rock said shaft for operating the type bar.
26. In a typewriting machine, the combination with a type bar and a key, of a device operated by the key, a universal bar for receiving a partial stroke from said device, an electric circuit closed by said partial stroke, and a magnet in said circuit for drawing said universal bar to complete its stroke to operate the type bar; means being provided for opening the circuit at the completion of the stroke of the universal bar.
27. In a typewriting machine, the combination of a type bar, an operating key, a universal bar, a connection between said universal bar and said key whereby the universal bar is given a partial stroke, said universal bar connected to the type bar to operate the same, an electric circuit, means for closing said electric circuit by said partial operation of the universal bar, and a magnet in said circuit for causing said universal bar to complete its stroke.
28. In a typewriting machine, the combination of a type bar, an operating key, a universal bar for receiving a partial stroke from the key, said universal bar connected to the type bar to operate the same, and means actuated by said partial stroke to complete the stroke of said universal bar.
29. In a typewriting machine, the combination with a type bar and a key, of a universal bar for receiving a partial stroke from the key, and means actuated by said partial stroke to complete the stroke of said universal bar; the type bar being operable by the universal bar during such completion of the stroke of the latter.
30. The combination of a key, a universal bar, means to enable the key to start the universal bar, a ratchet wheel operable by the universal bar, a source of power brought into action by the movement of the ratchet wheel, means for enabling said source of power to complete the movement of the universal bar and ratchet wheel, means cooperating with the ratchet wheel to shut off the source of power, and a type bar operable by said universal bar.
31. The combination of a type bar, a key, a universal bar, connections between the key and the universal bar to give a partial stroke to said bar, electrical connections to complete the movement of the universal bar, and means whereby the complete movement of the universal bar operates said connections to actuate the type bar.
32. In a typewriting machine, the combination with an operating key, of a universal bar given a partial stroke by the key, means connected to a source of power for completing the stroke of the universal bar; a type bar, and connections between the type bar and said universal bar to be operated thereby during such completion of the universal bar movement.
33. The combination of a key, a universal bar, a ratchet wheel operable by said universal bar, an electric circuit closable by the initial portion of the movement of said ratchet wheel, a magnet in said circuit for completing the movement of said universal bar, and a type bar operable by said magnet through said universal bar, said circuit being constructed to be opened by the final portion of the movement of the ratchet wheel.

CHARLES HERMAN VOGEL.
